UNITED STATES PATENT OFFICE.

CHARLES M. WOOLCOTT AND ALBERT E. WILMOT, OF NEW YORK, N. Y.,
ASSIGNORS TO THOMAS W. ROBERTSON AND CHARLES E. ONGLEY,
BOTH OF SAME PLACE.

CIRCUIT-CONTROLLER AND ALARM.

SPECIFICATION forming part of Letters Patent No. 445,306, dated January 27, 1891.

Application filed October 16, 1890. Serial No. 368,320. (No model.)

To all whom it may concern:

Be it known that we, CHARLES M. WOOLCOTT and ALBERT E. WILMOT, citizens of the United States, residing at New York, in the county 5 and State of New York, have invented a certain new and useful Improvement in Circuit-Controllers and Alarms, of which the following is a specification.

The object of our invention is to provide 10 means for changing the condition of an electrical circuit by a circuit-controller which is operated by the effect of moisture for signaling and other purposes; and the invention consists in a circuit-controller of conducting 15 material which is dissolved or softened by water.

The invention consists, further, in the combination of a circuit-controller which is dissolved or softened by water with an automatic 20 fire-extinguisher, sprinkler, or analogous device where there is constant danger of leakage and where it is important that the fact 25 of the leak should be known at once.

In the accompanying drawing, which illustrates the invention, the figure shows a sprinkler such as used in the Ongley fire-extinguishing system, which is adapted to give way at a predetermined temperature and flood the space near it with water, and our improved 30 circuit-controller supported thereby. The construction and operation of sprinklers of this character are well known and need not be specifically described. It sometimes happens that these and other similar sprinklers 35 leak when there has not been a sufficiently high temperature to cause them to operate. Said leak may be due to an accidental blow or strain or to corrosion of the metal from which they are made, and it is very desirable 40 to know of such leak immediately, so that it can be remedied and the flooding of the building avoided. Perfect means are provided by our improvement for accomplishing this desired result.

45 In the drawing, 1 is a sprinkler, connected to a water-pipe 2 in the ordinary way and forming an outlet from the water-pipe.

3 4 are two conducting-springs, supported

in any suitable way and terminating adjacent to the bottom of the sprinkler. As shown, 50 spring 3 is mounted on an insulating-block 5, and spring 4 is mounted directly on the body of the sprinkler, although this spring may also be insulated from the sprinkler; but this is not usually necessary, owing to the 55 electrical resistance offered by the joints between the sprinkler and water-pipe and between the sections of pipe. The wire 6 is connected to spring 3 and wire 7, which leads to a bell 8 or other electrical apparatus to be 60 operated, and a battery is connected to spring 4. The springs preferably terminate in spring-clips, as shown. Between the springs and supported in said clips is placed our circuit-controller 9, which is of such shape and size 65 as to catch any drops of water that may fall from the sprinklers. When used in connection with closed-circuit systems, which is the preferred arrangement, this circuit-controller is or may be of conducting material, and the 70 circuit may pass through it.

Pulverized sulphate of iron, pyrite of iron, or ordinary stove-blacking molded or formed into blocks or strips of proper size and shape is found well suited for our purpose, since 75 a drop or two of water on such strip so dissolves or softens the material that it gives away and opens the circuit. To give sufficient conductivity we may incorporate black oxide of iron or other conducting-powder in 80 the strip. In this arrangement the springs 3 4 have a tension away from the sprinkler; but the tension is insufficient to pull the spring-clips from the strip 9. The same material may be used in connection with an open 85 circuit by insulating the line from the strip 9—for example, by placing paper between 9 and one of the spring-clips which holds it and giving the springs a tension toward the sprinkler. Upon the giving away of 9 the circuit 90 can then be closed by contact being made between springs 3 and 4 or between spring 3 and the body of the sprinkler.

The circuit-controller, instead of being of a conducting material, may be of insulating 95 material, such as paper, which is sufficiently

stiff to hold the circuit-terminals when dry, but readily yields when softened by water, as above described.

In certain cases it may be desirable to apply a slight force to the circuit-controller to throw it out of line when it becomes weakened by moisture. This may be done, for example, by making the upper spring of the clip longer than the lower one and causing it to press down on the controller, as shown at 10; but ordinarily the weight of the device itself would be sufficient.

The operation of this device is clear, viz: If the sprinkler gives away suddenly in the ordinary manner, the circuit-controller is broken by the weight of the sprinkler and water and gives an alarm; but if a slight leak occurs, so small as to be hardly noticeable, and a drop or two falls onto and dissolves or softens the circuit-controller, the circuit is changed, as above described, rendering the alarm at the office or other locality or operating any other desired electrical device.

Evidently this circuit-controller may be used in any place where danger of leakage exists, and its utility is not confined to the application above described.

Having thus described our invention, what we claim is—

1. A circuit-controller of a conducting material which is dissolved or softened by water, in combination with circuit-terminals electrically connected thereby, substantially as described.

2. A circuit-controller of sulphate of iron

in which is incorporated a conducting-powder, substantially as described.

3. The combination, with a circuit containing an electrically-operated device, of circuit-terminals and a circuit-controller of a conducting material which is dissolved or softened by water, said circuit-controller being in the circuit and normally maintaining it closed, substantially as described.

4. The combination, with an automatic sprinkler, of an electric circuit having terminals at the sprinkler and a circuit-controller which is dissolved or softened by water between the terminals and holding them to maintain the normal condition of the circuit, substantially as described.

5. The combination, with a sprinkler, of springs mounted thereon, one being insulated from the body of the sprinkler, and a circuit-controller held below the sprinkler by said springs, substantially as described.

6. The combination of a sprinkler with springs or arms mounted thereon, one being insulated from the body of the sprinkler, clips at the outer end of said springs or arms, and a circuit-controller held in said clips below the sprinkler, substantially as described.

This specification signed and witnessed this 11th day of October, 1890.

CHARLES M. WOOLCOTT.
ALBERT E. WILMOT.
